UNITED STATES PATENT OFFICE

2,602,640

CONCRETE CUTTING TOOL

Joseph R. Colley, Chesterton, Ind.

Application November 25, 1946, Serial No. 712,224

1 Claim. (Cl. 255—62)

1

My invention relates to improvements in a concrete cutting tool and it more specifically comprises the structure described in the specification and pointed out in the annexed claims.

The purpose of my invention is to provide a cutting tool that projects radially from one side of a hexagon or round bar; that has a guiding portion on the bar in advance of the wedging portion; that uses a pneumatic drive for the tool which is held in the hands of the operator; and that, due to the rapid reciprocation of the tool, that portion of a concrete wall located between two adjacently drilled holes is rapidly removed.

With these and other related ends in view I illustrate in the accompanying drawing such an instance of adaptation as will disclose the broad underlying principles of the device without limiting myself to the specific details shown thereon and described herein.

Fig. 1 is a detached elevation of a portion of a concrete wall showing a group of pre-drilled holes in spaced-apart relation.

Fig. 2 is a cross section of Fig. 1, showing the cutting tool in position in one of the drilled holes.

Fig. 3 is a detached elevation of a tool with a pneumatic operated handle showing the entire tool.

Fig. 4 is an enlarged elevation of the end view of the tool in position in one of the preformed holes and showing the relation of that hole to a companion hole in spaced apart relation above the one that is occupied by the tool and a similar hole in spaced apart relation below the central hole in which the tool is placed.

Fig. 5 is an elevation of a slab of concrete showing a group of related pre-formed holes that outline a portion of the concrete wall that is to be removed, through the cutting of the material between holes.

In practically adapting my invention to its intended purpose, I may make whatever changes in the structure that the exigencies of varying conditions may demand without departing from the broad spirit of the invention.

A portion of a concrete wall 1 that is to be removed has a series of holes 2 drilled through the thickness of the wall, leaving untouched portion 3 between adjacent holes.

The cutting tool 6 projects radially from the hexagonal stem 4. This stem in front of the cutting edge 7 of the tool is the part 5 which first enters a preformed hole 2. The entering end 5 steadies the tool as it rapidly reciprocated by the tube 8 connected to a source of pneumatic pressure 9. A cutting edge 7 is formed on the front edge of the projecting portion 6.

There is always a great difficulty in puncturing a wall of concrete, similar to the diagram, Fig. 5.

The cutting member or fin 6 has an outwardly

and rearwardly inclined edge portion extending away from the pointed end 3 of the stem, and an outwardly and forwardly inclined edge portion meeting the first edge portion to form a sharp point, said first edge portion being beveled to form a cutting or wedging surface 7 that acts in two directions, radially and transversely at the same time.

It is immaterial how thick the concrete wall may be as the pilot end 5 of the tool always guides it so that the wedging portion 6 will rapidly remove the previously untouched portion 3. In fastening the tool in the pneumatic holder, the blade 6 is set at the desired angle or its angle may be changed by bodily twisting the pneumatic holder around its axis as needed. It is immaterial whether the concrete wall is either relatively thin or very thick.

In quarrying limestone, sandstone, or granite, or in preparing for the removal of a portion of a cement wall, the progress is simplified through the use of a large number of neighboring holes formed in such numbers as to entirely surround a given area which is to be removed. This is quickly done by a wedging action against the narrow wall that is not removed between the adjacent holes. When all the walls are removed by the wedging action of the edge 7 of the tool, the entire area is separated.

Without the use of my tool under the control of the pneumatic holder, the untouched portion 3 between adjacent holes 2 must be removed by hand chiseling, which is a laborious and expensive procedure.

What I claim is:

A concrete cutting tool comprising an elongated stem having a pointed end, a radially projecting blade mounted on the stem a short distance away from said pointed end, said blade having an outwardly and rearwardly inclined edge portion extending away from the pointed end of the stem, and an outwardly and forwardly inclined edge portion meeting the first edge portion to form a sharp point, said first edge portion being bevelled to form a cutting or wedge surface.

JOSEPH R. COLLEY.
